of Virginia

Filed Aug. 1, 1962, Ser. No. 71,128

Term of patent 14 years

(Cl. D52—3)

FIG.1

FIG.2

FIG.3

FIGURE 1 is a front perspective view of an automatic vending machine for greeting cards or the like showing my new design; and

FIGURE 2 is a side elevational view thereof; and

FIGURE 3 is an enlarged perspective view thereof with a portion of the housing broken away for convenience of illustration.

The essential features of my design reside in the portions shown in solid lines in the drawing. The undisclosed side of FIG. 2 is substantially the same in appearance as the side shown.

I claim:

The ornamental design for an automatic vending machine for greeting cards or the like, as shown and described.
